UNITED STATES PATENT OFFICE.

SHERWOOD HINDS, OF FORT WAYNE, INDIANA.

CURB-PUMP.

1,345,774.

Specification of Letters Patent.

Patented July 6, 1920.

Application filed September 26, 1917. Serial No. 193,259.

To all whom it may concern:

Be it known that I, SHERWOOD HINDS, a citizen of the United States, residing at Fort Wayne, in the county of Allen and State of Indiana, have invented certain new and useful Improvements in Curb-Pumps, of which the following is a specification.

This invention relates to a pump in which the operating mechanism is entirely inclosed but which is provided with an external hose and operating crank lock as one of the novel features of the construction. Other objects of the invention are to provide a double indicator which may be observed from both sides of the pump, and to provide an adjustable take-up and accuracy registering mechanism for varying the discharge of the pump upon each stroke thereof. Other novel objects will appear hereinafter.

20 The invention consists in the novel construction, combination and arrangement of the several parts.

In the accompanying drawings:

Figures 1, 2 and 3 are front, side and rear elevations respectively, of a pump constructed in accordance with the principles of the invention,

Fig. 4 is a sectional view of the dispensing cylinder and filter,

Fig. 5 is a sectional view of a portion of the pump showing the hose, crank handle and pump rack locking means,

Fig. 6 is an enlarged view of the upper portion of the pump casing,

Fig. 7 is a sectional view of the operating mechanism taken at right angles to that shown in Fig. 5,

Fig. 8 is a view partly in section showing the upper discharge valve,

Fig. 9 is a diagrammatic view to illustrate the operation of the mechanism,

Fig. 10 is a face view of the customer's dial,

Fig. 11 is a face view partly in section of the adjustable take-up mechanism, and

Fig. 12 is a sectional view of a portion of the mechanism shown in Fig. 11.

In many cities and places where liquids, particularly combustible liquids, are dispensed, there are strict ordinances and laws governing the use of the dispensing apparatus. One of the objects of the present invention is to provide a pump for dispensing gasoline, oil and the like, which is

entirely inclosed so that it may be located 55 along the side or curb of a thoroughfare with the least possible obstruction and without requiring a separate housing or a casing which must be opened and closed in order to operate the dispensing mechanism. Of course, it is necessary to have an operating 60 crank and a discharge hose, but in the present invention, these two members are permanently located on the outside of the casing. In a pump of this type it is desirable 65 to use a reciprocating type of pump and in order to preserve the accuracy of discharge it may be necessary to vary the length or stroke of the piston. To do this would also cause a variation of the throw of the indicator unless particular means is provided for taking this variation into account. In the present invention this is accomplished 70 by an expanding segment mechanism which, together with a take-up spring, makes constant 75 the throw of the indicator dial for all variations of the stroke.

For convenience in reference, this pump will be divided into a base 1, a middle portion 2, and a top 3. In the base is located 80 the well known pumping mechanism which comprises a pumping cylinder 4 in which a piston 5 is moved by means of a rod 6 attached to a rack 7. The piston is provided with openings 8 and a valve 9 for admitting fluid to the cylinder in one direction. At the bottom of the cylinder is a base forming a passage 10 in which is a foot valve 11 for admitting liquid from a suction pipe 12. At the top of the cylinder is a manifold 13 90 which connects it with the top of a centrifugal filter 14 having means forming an outer spiral passage, a filter screen 15 and a central passage 16 in which is a water or impurity discharge pipe extending through 95 the top, the passage communicating with the chamber 17 at the top from which extends a discharge pipe 18 leading through the middle portion of the pump and into the top 3 thereof (see Fig. 8) where there is a fitting 19, open at the top, provided with a seat for a valve 20. Above this valve is a threaded opening into which a pipe fitting 21 is inserted and a discharge hose 22 is attached thereto.

In order to control the valve 20 a stem 23 attached to the valve is pivoted to a lever 24 which is pivoted at one end to a block 25

- slidable upon a link 26 substantially parallel with the stem 23 and with a spring 27 tending to hold the block 25 downwardly upon an adjustable nut 28. The other end of the lever 24 is connected to a rod 29 which extends downwardly into the middle portion 2 of the pump where it is connected by means of a crank 30 with a shaft 31 extending through the pump casing and having a handle 32 on the outside thereof. The rotation of this handle opens or closes the valve 20 and of course the valve must be opened before liquid can be discharged from the pump. It is closed when the pump is not in use to prevent leakage and evaporation.
- In the middle portion of the pump is an operating shaft 33 to which a pinion 34 is secured that meshes with the rack 7. This shaft extends through the pump casing and an operating crank 35 is secured to it with a pivoted handle 36 which may be rotated to take two positions, one as shown in Fig. 7, and the other opposite thereto, as shown in Fig. 2, and in the latter position it could not be operated except a portion of a revolution, because it would engage the casing of the pump. In order to hold the handle and the crank 35 so that it cannot be operated, and in order also to lock the discharge hose in position, the latter is provided with a nozzle 37 which may be seated between a pair of hooks 38 projecting from one side of the pump casing (see Figs. 3 and 5), and mounted in the casing is an arm 39 provided with an eye 40 for receiving the handle 36 and a hook 41 formed with an outer bent portion 42 which is movable across the outer sides of the hooks 38, the arm 39 and the hook 41 being connected together for simultaneous rotation by means of a shaft 43. When the nozzle 37 is placed in the hooks 38 and the handle 36 is engaged in the eye 40, the nozzle will be locked in place by the bent portion 42 of the hook 41 and a lock 44, of any well known form, is provided for securing the parts in this locked position from which they can be disengaged only by the opening of the lock, whereupon the arm 39 will take the dotted position shown in Fig. 2, and the bent portion 42 of the hook 41 will take the dotted position shown in Fig. 5.
- Provision is also made for insuring that when the handle and the hose are in their locked position, the pump itself will be in a particular position, namely with the rack and the piston at the lower end of their stroke. Secured to the inner end of hook 41 is an eccentric 45 which is engaged by a member 46 pivoted on the inside of the casing of the pump and formed with a foot 47 which can be moved to engage the top of the rack 7 only in its lowermost position. When the hook 41 is rotated to release the nozzle of the hose, the eccentric 45 will also

be rotated, thereby engaging the member 46 and move it laterally so that the foot 47 will be free from engagement with the rack.

In order to vary the stroke of the pump piston to pump different amounts, as for example either one gallon or two gallons, a link 48 is pivoted on a block 49 and can be moved into or out of the path of the rack 7 by means of a crank 50 attached to a shaft 51 which extends through the casing and has an indicator 52 on the outside thereof to show the position of the link. This block 49 is supported by a threaded rod 53 which in turn is threaded through a web of the pump casing in position to be engaged by the rack 7, the end of the rod 53 thereby constituting an adjustable stop for the rack when the link 48 is moved out of engaging position. The position of the block 49 and also of the rod 53 can be independently varied and maintained by means of the lock nuts 54, the block being held against rotation by means of a pin 55 which extends through a perforated tail-piece 56 extending from the block. When the link 48 is moved to take the dotted line position, as shown by Fig. 9, the rack 7 will be limited in its upward movement by the rod 53.

The operator of this pump is usually on one side of it while the customer is on the other side and an indicating dial is provided on each of the opposite sides for them. The customer's dial 57 is shown more clearly in Fig. 10 and the operator's dial 58, which comprises simply a pointer 59, is shown in Fig. 3. The customer's dial is also provided with a pointer 60 which is mounted on a common shaft 61 with the other pointer 59. Secured to the operating shaft 33 is a plate 61' formed with outwardly curved slots 62 in which pins 63 are slidable. These pins are secured to circular segments 64 and the segments can be moved radially outward from the axis of shaft 33 by a relative movement of the plate 61' and the said segments. To one of the segments a flexible band 65, preferably of metal, is secured by means of a fastening device 66. This band or ribbon 65 is wound upon and secured to a drum 67 which in turn is rotatably mounted upon a hub portion 68 of a fixed plate 69, the face of which constitutes the dial 57. Secured to the plate 69 and the drum 67 is a spring 70 which tends to keep the band 65 taut and to draw upwardly on it to take up the lost motion between the rack 7 and the driving pinion 34. In the plate 69, and extending around the graduations of the dial 57, is a circular slot 71 through which projects a pointer 72 extending from the ribbon drum 67. At one end of the slot is the designation 0 and at other points around the slot are designations such as $\frac{1}{2}$ gal., 1 gal., and 2 gals. designating the quantities pumped for a given position of the pointer 72, it being ob-

vious that the pointer will assume these positions upon the actuation of the pump rack because of the connection of the band 65.

Freely rotatable on the hub of the member 69 between it and the ribbon drum 67 is a Geneva stop gear 73 which has lugs 74 adapted to be engaged by a projection 75 of the ribbon drum 67. This gear also has rearwardly extending toothed portions 76 which are spaced from the lugs 74 and at the bottom of the plate 69, as shown in Fig. 12, is a Geneva pinion 77 with which the gear 73 engages to rotate the pinion a predetermined amount upon each engagement of the toothed portion 76 with it. As the pump described is a two gallon measure and as it may be set to pump either one or two gallons at each stroke, by the adjustment of the member 52, which controls link 48, it is obvious that the Geneva pinion must be rotated twice for a full stroke of the pump; in other words, if the ribbon drum 67 is simply rotated until the pointer 72 reaches the one gallon mark, the stop 75 will engage only the uppermost lug 74 (see Fig. 10) which will move the lowermost toothed portion 76 to engage the pinion 77; but if the stop 75 is moved the entire length of the slot 71, both toothed portions 76 will engage the pinion 77 causing it to be twice actuated. Of course, the reverse rotation of the Geneva stop gear 73 engages the pinion 77 and moves it backwardly the same amount so that the gear 73 is simply oscillated back and forth one or two unit spaces by the engagement of stop 75, depending upon the length of stroke of the pump. Meshing with the pinion 77 is a gear 78 which carries a pawl 79 and this pawl engages a ratchet gear 80 fixed to the shaft 61. The rotation of the gear 78 in one direction causes the pawl 79 to actuate the ratchet gear 80 and cause a corresponding rotation of the pointers 59 and 60 which are attached to the shaft 61. Adjacent the ratchet gear 80 is a fixed member 81 which may be secured to the hub extension 68 of the plate member 69, and mounted on this member 81 is a holding pawl 82 which engages the ratchet gear 80 and prevents its reverse rotation when the actuating pawl 79 is moved reversely and idly over the gear.

The ribbon drum 67 is preferably formed with a hub extension 83 upon which is freely mounted a driving gear 84. Between this gear and the ribbon drum 67 is a spring pressed roller clutch 85 which causes the rotation of the gear 84 when the ribbon drum is rotated in one direction. Between the fixed member 81 and this gear 84 is a roller clutch 86 which prevents the rotation of the gear 84 in the reverse direction. Meshing with the gear 84 is a spur and bevel pinion 87 which is directly connected by a driving member 88 with a register 89 visi-

ble from the outside of the casing by raising a covering lid 89' as shown in Figs. 2 and 3. As the driving gear 84 is actuated only in one direction of rotation and as the mechanism described is a single action pump, it is obvious that the register will accurately record the total amount discharged by the pump, even though an insufficient quantity has been discharged to cause the units registers at the front and rear of the pump to indicate.

At the top of the pump is a globe 90 for containing an electric lamp which is preferably flattened to accommodate designating marks and leading therefrom is a conduit 91 for containing conductors 92 to supply current to an electric lamp within the globe. The dials 57 and 58 are preferably covered with glass and at the operator's end of the shaft 61 is a knob 93 by means of which the pointers 59 and 60 can be freely rotated in one direction to set them at the zero points. This is desirable for the reason that when a customer buys a quantity of the liquid dispensed, the pointers are set at zero marks 90 and the operation of the pump, as above described will cause the actuation of the pointers to record the units of the quantity pumped, whereupon the pointers can again be set upon the zero marks without in any way affecting the quantity register 89 which records the total amount pumped.

In varying the length of stroke of the pump rack to insure the accuracy of the pump, it is obvious that the graduation of the slot 71 would not remain the same for the different lengths of stroke; that is, if the pump were set so that the pointer 72 would register exactly with the two gallon graduation on the slot 71 and then it were found that it would be necessary to increase the length of stroke of the pump in order to pump exactly two gallons, the pointer 72 would not stop at the two gallon mark when the pump stroke was increased unless some adjusting means were provided for taking care of the increased stroke. This is the object and function of the adjustable circular segments 64 which are attached to the plate 61, for by moving them inwardly and outwardly the length of the path of travel of the pointer 72 may be varied whenever the length of stroke of the pump rack is varied so that the pointer will always register with the graduations of the slot thereby insuring also that the total register 89 will accurately record the amount pumped. Briefly stated it may be said that the segments 64 will be moved inwardly when the length of the pump stroke is increased and vice versa.

In operation, assuming the hose and the crank handle to be locked, the lock 44 is first operated to release the arm 39 which allows the arm and the hook 41 connected therewith to be rotated thereby freeing the han-

dle 36 of the crank 35 and permitting the disengagement of the nozzle 37 from the hooks 38. The rotation of this hook 41 also releases the rack locking member 46 by the engagement of the eccentric 45 therewith, moving the foot 47 out of engagement with the top of the rack. The handle 36 is then rotated from its locking position to the operating position, as shown in Fig. 7, the valve 20 is raised by the operation of the arm 32 at the rear side of the pump, the indicator 52 is turned to the right or left to position the link 48 so that the pump rack can be operated for half its stroke or a full stroke, and the indicators 59 and 60 may be set at zero position on their dials by the rotation of the knob 93 at the rear of the pump. The crank 35 is then operated to raise the rack 7 which draws the liquid to be discharged from the pipe 12 into the pump cylinder 4 and forces the liquid through the filter 14 and the pipe 18 past the valve 20 and through the discharge walls 22. The reciprocation of the rack 7 causes the actuation of the units registering mechanism which records the number of units of measure (gallons) of the fluid pumped and also the actuation of the registering counter which thereupon measures the entire discharge of the pump regardless of the number of units measure pumped. The various adjustments for the accuracy of the mechanisms are, of course, made whenever necessary, it being observed, however, that with this style of pump, it is unnecessary to have any access whatever to the interior of the casing of the pump in order to effect the ordinary operation thereof. In locking the pump, the various unlocking operations above set forth are practically reversed, the rack 7 being locked only at the lowermost end of the stroke and the crank handle and the nozzle being locked in position when the arm 39 is rotated upwardly to engage the handle 36 in the eye 40 thereof from which the parts can be unlocked only by the insertion of a proper key in the lock 44. In the locked position, it will be observed that the handle 36 is held tightly against the side of the pump casing where it is not easily engaged.

What I claim is:

1. A curb pump comprising pumping mechanism, an operating member, a discharge hose, a casing entirely inclosing the entire pumping mechanism with the exception of the operating member and the said hose, and common locking means for the member and the hose.
2. In a curb pump, the combination with pumping mechanism including an operating member and a discharge hose, of a casing entirely inclosing the mechanism with the exception of the member and the hose, locking means comprising a rotatable hook for

engaging the hose and a rotatable arm connected therewith for engaging the handle, and a key-operated lock for controlling the position of the said rotatable members.

3. In liquid dispensing apparatus, pumping mechanism comprising a reciprocable rack, an operating crank, and a discharge hose, of a closed casing for inclosing the entire pumping mechanism except the crank and the hose, rotatable locking means for the crank and hose, an eccentric in connection with the locking means, and a member engaged by the eccentric having a portion to engage the rack and lock it in position when the crank and hose are locked.

4. The combination with pumping mechanism comprising a reciprocable member, of a closed casing for the pumping mechanism, a rotatable member operated from the outside of the casing, an eccentric carried by the rotatable member, and a member operated by the eccentric and having a projection to engage the rack for holding it in locked position.

5. The combination with pumping mechanism including an operating crank, a reciprocable rack, and a discharge hose, of a closed casing for inclosing the pump with the exception of the crank and the hose, a valve within the casing at the top thereof having means for operating it from without the casing to control the discharge of liquid from the said hose, and common locking means for engaging the crank, the rack, and the hose.

6. In pumping mechanism, the combination with a reciprocable member, of means for varying the length of stroke thereof to pump different units of quantity, said means comprising an adjustable pin which limits the stroke of the member, and a rotatable link carried by the pin for engaging the reciprocable member in one position but movable out of the path thereof so that the said member engages the pin.

7. In pumping mechanism, the combination with a reciprocable member, of a double stop therefor comprising an adjustable threaded pin, a block adjustably mounted on the pin, and a member carried by the block and movable into and out of the path of the reciprocable member.

8. In a pump, the combination with a reciprocable member, of a double stop for said member comprising an adjustable pin, and a pivoted member separately adjustable on the pin and movable into and out of position to engage the reciprocable member.

In testimony whereof I have signed my name to this specification on this 5 day of September, A. D. 1917.

SHERWOOD HINDS.
